UNITED STATES PATENT OFFICE.

WILLIS SMITH FARNSWORTH, OF SAN FRANCISCO, CALIFORNIA, ASSIGNOR TO COIN CONTROLLED LOCK COMPANY, OF SAN FRANCISCO, CALIFORNIA, A CORPORATION OF CALIFORNIA.

LOCK-GUARD.

1,308,734.

Specification of Letters Patent.

Patented July 1, 1919.

Application filed April 15, 1913. Serial No. 761,165.

To all whom it may concern:

Be it known that I, WILLIS S. FARNSWORTH, a citizen of the United States, residing in the city and county of San Francisco and State of California, have invented new and useful Improvements in Lock-Guards, of which the following is a specification.

This invention relates to a lock guard, and particularly pertains to a device for preventing the re-operation of the lock after being operated without the key being first partially removed from the lock and re-inserted therein.

It is the object of this invention to provide a device of the above character, which is especially applicable for use in connection with coin-controlled locks of that type in which a cylinder lock is employed, and having coin-controlled means for preventing the operation of the lock and withdrawal of the key therefrom only on depositing of a certain coin, and which is adapted to re-engage the cylinder and prevent the re-operation of the lock when the key is turned to unlock the lock.

It has been found that persons operating locks of the above type inadvertently turn the key backward before removing it from the lock, after having deposited a coin and thrown the bolt, thereby accidentally unlocking the lock, thus losing the coin. It is the purpose of this invention to provide a means for preventing this accidental operation of the lock, which is so constructed as to necessitate the partial removal of the key from the lock and its re-insertion therein before the lock can be unlocked. A further object is to provide a device of the above character which is simple in construction and operation and not liable to get out of order, and which may be easily attached to the lock with but slight alteration of the lock structure. Further objects will appear hereinafter.

The invention comprises a spring-operated means for normally engaging the cylinder of a lock, adapted to be released on the insertion of the key in the lock to permit the rotation of the cylinder in one direction, and which will operate on the reverse movement of the cylinder to reengage the cylinder and thereby prevent its re-opera-

tion until after the key has been withdrawn from the lock and re-inserted therein. 55

The invention further consists of the parts and the construction and combination of parts as hereinafter more fully described and claimed, having reference to the accompanying drawings, in which— 60

Figure 1 is a rear view of a coin-operated lock with the bolt in its retracted position, showing the invention as applied.

Fig. 2 is a side elevation of the same.

Fig. 3 is a rear view showing the bolt in 65 its advanced or locked position.

Fig. 4 is a detail in elevation of the lock guard attachment in its released position, prior to the turning of the key to lock the lock. 70

Fig. 5 is a detail side view corresponding to Fig. 4.

Fig. 6 is a detail in elevation showing the lock guard in its engaged position, prior to the withdrawal of the key from the lock. 75

Fig. 7 is a detail side view corresponding to Fig. 6.

Fig. 8 is a detail in elevation of the lock guard as positioned after the key has been removed from the lock. 80

Fig. 9 is a detail in elevation of the lock guard in the position assumed when the key is re-inserted in the lock.

Fig. 10 is a partial vertical section and side elevation corresponding to Fig. 9. 85

In the drawings the lock is shown as consisting of an escutcheon plate A, a cylinder casing B mounted on the rear side thereof, a cylinder C revolvably mounted in the casing B and having a keyhole D therein 90 adapted to receive a key E by which the cylinder C may be rotated, a series of tumblers F and G mounted in the casing B and cylinder C, a bit H on the cylinder C, and a lock-bolt I engaged by the bit H and reciprocally mounted at the rear side of the escutcheon plate A. 95

The lock consisting of the casing B, cylinder C, and tumblers F and G, is of the well-known cylinder type, in which the tumblers 100 F and G are adapted to be operated by the key E to position their abutting ends in alignment with the circumferential wall of the cylinder C, to permit the turning of the latter in the casing B and the consequent operation 105 of the bolt I in either direction, as is well-

known in locks of this character. In locks of this type, when the cylinder C is turned to dispose the tumblers F and G out of alignment with each other, the key E will be securely held in the lock against being withdrawn. This fact has been taken advantage of in applying the coin-operated mechanism, which is designed to normally retain the cylinder C in such position that the tumblers G will be out of alignment with the tumblers F, and the key E will be disposed at an incline; in which position the bolt I will be retracted and held against advancement. This positioning of the parts is shown 10 in Fig. 1. This mechanism is constructed as follows:

Mounted on the back of the escutcheon plate A, on opposite sides of the cylinder C, are downwardly depending arms 2 and 3, the upper ends of which are pivotally connected to a face plate 4 on the outer face of the plate A, by means of screws 5 which pass through curved slots 6 in the plate A. The slots 6 act in conjunction with the screws 5 to limit the rocking movement of the face plate 4 and the lock cylinder C in either direction; the plate 4 being connected to the cylinder C. The arms 2 and 3 extend downwardly adjacent to the rear 20 side of the escutcheon plate A; the arm 3 being guided at its lower end by an outwardly extending pin 7, which extends through a vertical slot 8, in a plate 9, formed on the lower end of the arm 3; the pin 7 being rigid with the escutcheon plate A.

The inner edge of the lower end of the arm 2 contacts the pin 7 and is held thereagainst by means of a helical spring 10, attached at 40 one end to the arm 2 and at the other end to the arm 3, and is always under tension. The pin 7 thus serves to limit the inward movement of the arm 2 and also limits its downward movement when actuated by the plate 45 4, by reason of its engagement with a shoulder 11 formed on the arm 2. It will be observed that the arm 2 may be rocked outwardly away from the pin 7, in opposition to the spring 10.

Carried on the lower end of the arm 2 is an inwardly extending plate 12, which projects over the lower end of the arm 3 and forms a coin-socket between the lower ends 55 of the arms 2 and 3, in which a coin may be inserted through a slot 13 formed in the escutcheon plate A. A coin deposited in the slot 13 is designed to come to rest on a shoulder or abutment 14, formed on the inner edge of the arm 3, where it is supported 60 by reason of its opposite edge bearing against the inner edge of the arm 2; the coin indicated at J resting on the shoulder 14 below an inwardly extending flange or coin-pusher 15, on the upper edge of the plate 12 and operated by the arm 2.

When the key E is in the lock and the bolt I is in its retracted position, the lower ends of the arms 2 and 3 will be positioned as shown in Fig. 1; in which position downward movement of the arm 2 a sufficient distance to allow actuation of the bolt is prevented by means of the pin 7 and shoulder 11, so as to prevent the plate 4 and the lock cylinder C being rocked by the key E sufficiently far to allow the latter to be disposed in its vertical position. By this construction the key is prevented from being withdrawn from the lock and also locked against movement, thereby preventing the operation of the bolt I.

When it is desired to throw the bolt I and withdraw the key E, a coin J of a certain diameter or denomination is deposited in the slot 13 where it comes to rest upon the abutment 14 between the lower ends of the arms 2 and 3, as before described, and as shown in Fig. 1; the shoulder 11 being positioned a short distance above the pin 7 to permit of a limited downward movement of the arm 2 and consequent slight rotation of the plate 4 and cylinder C. This movement of the plate 4 is effected by turning the key E after the coin J is deposited, in such manner as to move the arm 2 in a downward direction and the arm 3 in an upward direction. The upward movement of the arm 3 carries the coin J therewith, so as to bring its upper edge into contact with the lower edge of the flange 15 on the plate 12. The downward movement of the arm 2 causes the flange 15 to engage the coin J and move it downwardly in opposition to the arm 3, causing it to press against the shoulder 14 and force the arm 2 away from the arm 3, so as to cause the shoulder 11 to clear the pin 7. 105 This will permit of a continued rotary movement of the key E, the plate 4, and cylinder C, so as to throw the bolt I into the locked position and dispose the key E in the vertical position, which will allow of its being withdrawn from the lock. In thus advancing the bolt I, the arm 3 moves up and the arm 2 down. The coin on passing over the abutment 14 falls upon a stop-shoulder 16 on the inner edge of the lower end of the 110 arm 3, where it comes to rest with its opposite edge against the pin 7, as shown in Fig. 3.

The essence of the present invention resides in providing means for automatically locking the cylinder C against rotation when the parts are in the position just described, which means is adapted to necessitate removal of the key from the lock and its reinsertion therein in order to retract the bolt 125 I. This means is here shown as consisting of a plate spring 17 mounted upon the upper side of the casing B and extending downwardly opposite the rear end of the cylinder C; the lower end of the plate spring 17 hav- 130

ing laterally extending portions 18 and 19, formed with inturned flanges 20 and 21 on their ends, extending on opposite sides of the outer end of the casing B. The flanges 5 20 and 21 on the members 18 and 19 are provided for the purpose of limiting the side-wise movement of the spring 17, as will be later described.

Formed on the lower edge of the member 10 19 is an inturned flange 22, which is so disposed as to extend into a channel 23 formed in the end of the cylinder C, when the cylinder C is positioned as shown in Figs. 3 and 6; that is to say, when the cylinder C 15 is so disposed as to position the channel 23 horizontally, and the keyhole D vertically. A downwardly extending portion or finger 24 is formed on the spring 17, which extends alongside of the keyhole D, as shown in 20 Figs. 1 and 4, and is adapted to be engaged by the end of the key when the latter is inserted in the lock, to move the spring 17 outwardly and to be engaged by the key when the latter is turned to its withdrawing position, to move the spring 17 laterally.

The operation of the lock guard is as follows: Assuming the parts to be in the position shown in Figs. 1-4 and 5, in which position the key E is in the keyhole D and the 30 cylinder C is turned to dispose the key E in an angular position and retain the lock-bolt I in its retracted position. The plate spring 17 will then be disposed in its vertical position, with the flange 22 resting on the end 35 of the cylinder C and the finger 24 projecting to one side of the end of the key E, which extends a short distance through the rear end of the cylinder C. On the depositing of the coin in the lock and the rotation 40 of the cylinder C by the key, as before described, the outer end of the key will engage the finger 24, so as to rock the spring 17 from the position shown in Fig. 4 into the position shown in Figs. 6 and 7, whereupon 45 the flange 22 will move into engagement with the channel 23 on the end of the cylinder C, and thereby lock the latter against rotation. The parts will then be positioned as shown in Figs. 6 and 7. The key E may now be 50 withdrawn from the lock, and when this occurs the spring 17 will be restored by its own resiliency to its normal vertical position, as shown in Fig. 8, in which position the finger 24 will extend over the keyhole D 55 in the cylinder C, and the flange 22 will extend into the channel 23 on the cylinder C.

On the re-insertion of the key E to operate the lock, the outer end of the key contacts the inner face of the finger 24, and operates 60 to move the lower end of the spring 17 outwardly and thereby disengages the flange 22 from the channel 23, as shown in Figs. 9 and 10. The cylinder C may then be freely turned to retract the bolt I and unlock the 65 lock; the end of the key moving to one side

of the finger 24, into the position shown in Fig. 4, on this operation, so as to reposition the finger 24 to one side of the end of the key, in readiness for another operation.

Having thus described my invention, what 70 I claim and desire to secure by Letters Patent is:

1. The combination in a lock having a cylinder and a key therefor, of detent means adapted to engage the cylinder when the latter is turned in one position to lock the cylinder against rotation, said detent means constructed and arranged to be actuated by the insertion of the key into the lock to release the cylinder, and said detent means operable 75 to engage the cylinder when the key is in the lock and prevent the re-operation of the lock until the key has been withdrawn and reinserted into the lock, said last-named means including a lockable spring plate extendible 80 directly into the path of the end of the key.

2. The combination with a key, cylinder and tumblers of a lock, of means co-operating with the cylinder and directly with the end 85 of the key to permit the rotation of the cylinder only on the initial insertion of a key therein, and which will operate to lock the cylinder against rotation after the lock has been operated before removal of the key 90 therefrom.

3. In a lock, the combination of a key operated bolt, means for preventing withdrawal of the key when the bolt is in unlocked position, and means disposed for actuation by direct engagement with the end 100 of the key for preventing movement of the bolt from locked to unlocked position until the key has been withdrawn and reinserted in the lock.

4. In a lock, the combination of a key operated bolt, and means rendered operative upon movement of the bolt into locked position and prior to the withdrawal of the key from the lock to prevent unlocking movement of said bolt, said means being adapted 105 to be released directly by the end of the key upon complete insertion thereof into the lock.

5. In a lock, the combination of a key operated locking bolt, a key, a key-receiving cylinder, connections between the cylinder and said bolt to move said bolt to locking position, means automatically operative to lock the cylinder against rotation when the locking bolt has been moved to locked position thereby preventing rotation of the cylinder until and after the key has been withdrawn, said last mentioned locking means being automatically released by direct engagement with the end of the key upon insertion of the key into the cylinder.

6. In a lock, the combination of a key operated locking bolt, a cylinder having a key receiving-hole therein, operative connections between the bolt and cylinder, and a 130

latch overlying one end of the key hole adapted to automatically engage in a notch in the cylinder when the bolt is in locked position to prevent rotation of the cylinder, 5 said latch being adapted to be released by direct engagement of the end of the key with said overlying portion upon reinsertion of the key into the cylinder.

7. In a lock, the combination of a key operated locking bolt, a key cylinder, connections between the bolt and cylinder, and a spring-pressed latch adapted to engage a notch in the cylinder to lock said cylinder when the bolt is moved to locked position, 10 15 said latch being constructed to permit withdrawal of the key from the cylinder but to be directly engaged by the end of the key upon reinsertion thereof, whereby the latch is released to permit the unlocking of the 20 bolt.

8. In a lock, the combination of a key operated locking bolt, a key cylinder, and a latch adapted to automatically engage with the cylinder upon movement of the cylinder 25 and bolt to locking position and before withdrawal of the key from the cylinder, whereby to prevent unlocking of the lock, said latch being adapted to be released by the end of the key only upon reinsertion of the key 30 into the cylinder to thereupon permit the lock to be unlocked.

9. In a lock, the combination of a key operated locking bolt, a cylinder having a key receiving hole therethrough, operative connections 35 between the bolt and cylinder, and a latch overlying one end of the key hole adapted to automatically engage in a notch in the cylinder when the bolt is in locked position to prevent rotation of the cylinder, 40 said latch being adapted to be released by direct engagement with the end of the key upon reinsertion of the key into the cylinder.

10. In a lock, the combination of a key operated locking bolt, a cylinder having a key receiving hole therein, operative connections 45 between the bolt and cylinder, and a resilient latch overlying one end of the key hole adapted to automatically engage in a notch in the cylinder when the bolt is in locked 50 position to prevent rotation of the cylinder, said latch being adapted to be released from

the notch by direct engagement of the end of the key with said overlying portion upon reinsertion of the key into the cylinder.

11. In a lock, the combination of a key operated locking bolt, a cylinder having a key receiving hole therein, means preventing withdrawal of the key from the cylinder when the bolt is in unlocked position, operative connections between the bolt and cylinder, 60 a resilient latch overlying one end of the key hole when the bolt is in unlocked position and adapted to be forced to one side of the key hole when the bolt is in locked position, means engaged by said latch for preventing movement of the bolt from locked to unlocked position until the key has been withdrawn from the lock to permit the latch to assume its position over the key hole, and reinserted thereinto to engage the same. 65 70

12. In a lock, the combination of a key operated locking bolt, a cylinder having a key receiving hole therein, operative connections between the bolt and cylinder, and a latch overlying one end of the key hole 75 adapted to automatically engage when the bolt is in locked position with a notch formed in the end of the cylinder to thereby prevent rotation of the cylinder, said latch being adapted upon withdrawal of the key 80 to automatically align with said key receiving hole so as to be released by direct engagement of the end of the key with said overlying portion upon insertion of the key into the cylinder. 85

13. A lock comprising a key operated bolt, means for operating said bolt, and resilient means adapted to be deflected both longitudinally and laterally of said operating means for engaging said operating means 90 and preventing movement thereof to operate said bolt from locked to unlocked position until the key has been withdrawn and reinserted into the lock.

In testimony whereof I have hereunto set 95 my hand in the presence of two subscribing witnesses.
